UNITED STATES PATENT OFFICE

FREDERICK H. GAUTSCHI, OF VAN NUYS, CALIFORNIA

DESIGN FOR A COLONIC EXCRETA RECEPTACLE

Application filed March 7, 1932. Serial No. 43,110. Term of patent 14 years.

● *To all whom it may concern:*

Be it known that I, FREDERICK H. GAUTSCHI, a citizen of the United States, residing at Van Nuys, in the county of Los Angeles and State of California, have invented a new, original, and ornamental Design for a Colonic Excreta Receptacle, of which the following is a specification, reference being had to the accompanying drawing, forming a part thereof.

Figure 1 is a top plan view of a colonic excreta receptacle showing my new design.

Fig. 2 is a side elevation thereof.

Fig. 3 is an end elevational view of the same looking from the left hand side toward the right hand side of Fig. 2.

Fig. 4 is an end elevational view looking from the right hand side toward the left hand side of Fig. 2.

I claim:

The ornamental design for a colonic excreta receptacle substantially as shown.

Signed at Van Nuys, in the county of Los Angeles and State of California, this 29 day of February, 1932.

FREDERICK H. GAUTSCHI.
